HERBERT CORBALL, OF PARKVIEW, HELENSBURGH, SCOTLAND, ASSIGNEE TO THE
SINGER MANUFACTURING COMPANY, A CORPORATION OF NEW JERSEY.

SEWING-MACHINE.

1,243,921.

Specification of Letters Patent. Patented Oct. 23, 1917.

Application filed May 22, 1914. Serial No. 840,170.

To all whom it may concern:

Be it known that I, HERBERT CORBALL, a subject of the King of the United Kingdom of Great Britain and Ireland, and residing at Parkview, Helensburgh, Dumbartonshire, Scotland, have invented certain new and useful Improvements in Sewing-Machines, of which the following is a specification, reference being had therein to the accompanying drawings.

This invention relates to improvements in multiple needle sewing machines, and particularly to that class of machines in which means are provided for throwing one of the needles temporarily out of action while the other or others continue to reciprocate.

The improvements are adapted primarily for use in connection with two-needle sewing machines for simultaneously forming two independent seams or rows of stitches. To permit the formation of angular seams in a machine of this class, it is advantageous to temporarily disconnect one of the needle-bars from its actuating mechanism without stopping the machine. With this object in view the present improvements provide means whereby a reciprocatory driving element which embraces both of the needle-bars and which is provided with spring-pressed locking members automatically movable into engagement with each of said needle-bars, is employed in connection with selective retracting members adapted to utilize the motion of the driving element to retract the locking means from either or both of the needle-bars during the operation of the machine. The released bar is thrown upward out of register with the locking means by means of a spring which surrounds the same, said bar being returned to locking position by manual pressure upon the same against the action of its spring.

In the drawings Figure 1 is a front elevation of the head of a machine arm with the improvements applied thereto; and Fig. 2 is a side elevation of the parts shown in Fig. 1. Fig. 3 is a horizontal section on the line $\alpha-\alpha$, Fig. 1.

Referring to the drawings, the two needle-bars 1 are shown mounted to reciprocate within the head B of overhanging arm A, both of said needle-bars being embraced by a yoke 2, which, in turn, is operatively connected with a crank 3 on the upper or main driving shaft of the machine. The yoke 2

is formed with two orifices 4 within which move the spring-pressed locking pins 5, one end of each pin being adapted to enter socket 6 in the corresponding needle-bar, a flange 7 on each pin serving to limit the movement thereof within the needle-bar socket under the action of spring 7*. Each needle-bar is provided with a longitudinal shallow groove 1* to receive the end of a screw-pin 8, threaded in the yoke, which prevents accidental rotation of the needle-bar when the latter is uncoupled. A cap 8 secured to the face of the yoke by means of screw 9 is provided with projecting bushings 8* through which pass the locking pins, the outer ends of each pin being enlarged, or provided, as in the present instance, with a beveled thumb-nut 10 and a stop-nut 11 at the rear thereof.

Intermediate the thumb-nut 10 and the cap 8, and secured in fixed position upon the head B by means of screws 12, is a bracket-plate 13 formed with longitudinal apertures 14 within which the bushings 8* and locking pins 5 reciprocate during the movement of yoke 2. Extending laterally from the bracket-plate are upper and lower guide-arms 15 and 16, each arm being apertured to receive two sliding rods 17 each of which carries at its lower end a forked wedge 18 adapted to engage the nut 10 on one of the locking pins 5 to retract the same from the needle-bar. Each wedge member is normally held upward, out of effective position with respect to the locking pin with which it registers, by means of a light coiled spring 19 which surrounds the slide-rod intermediate the lower guide-arm 16 and a stop-pin 20 fitted within a transverse aperture in said rod. To the upper end of each slide-rod 17 is secured, by screw 21, a finger-piece 22, by means of which the rod may be depressed to carry its wedge member into effective position with respect to the locking pin. It will be seen that each wedge device is adapted to utilize the motion of the driving yoke 2 to retract the locking means from the needle-bar, inasmuch as the depression of either slide-rod 17 by means of finger-piece 22 will so position the wedge 18 that upon the rise of yoke 2 the thumb-nut 10 will ride up the inclined face of the forked wedge to retract the locking pin from the transverse socket of the needle-bar.

When either of the locking pins 5 is with-

drawn from its needle-bar by the action of one of the wedge devices, the bar is moved upwardly and out of register with the pin, through the action of a surrounding helical 5 spring 23. The lower end of each spring 23 rests upon the upper face of yoke member 2, and its upper end abuts a collar 24 fixed upon the needle bar by means of a clamping screw 25. The spring is ineffective so long 10 as the locking pin is within its socket 6 in the needle-bar, but immediately after the retraction of said pin, the spring will lift the bar relatively to the yoke, so that the socket 6 will be maintained out of register with the 15 pin until the bar is depressed.

For depressing each needle-bar to re-establish the operative connection between the same and the yoke 2, there is fitted on the head B of the bracket-arm a tubular post 26, 20 which is held in fixed position by means of a screw 27 and a stud 28. The post receives a sliding pin 29 fixed within a cap 30 embracing the upper ends of the needle-bars. A spring 31 interposed between the base of 25 the tubular post and the lower end of pin 29 tends to raise the cap 30, the movement of the latter being limited by a stop-pin 31^x fitted within a transverse aperture formed in the tubular post 26, each end thereof entering a slot formed in the cap. When the 30 cap is depressed the uncoupled needle-bar or bars will be moved downwardly so that the yoke, in its upward movement, will carry the locking pin or pins into register with 35 the needle-bar socket or sockets. It will be understood that the wedge devices 18 may be connected to a knee or foot-operated member, and also that if desired, similar means may be connected to the cap 30 for depressing 40 each uncoupled needle-bar.

By the foregoing construction and arrangement of parts, either or both of the needle-bars may be thrown out of action and back into action during the operation 45 of the machine, the controlling means for such purpose being mounted on the head of the sewing machine and readily accessible to the hand of the operator.

The invention is susceptible of various 50 changes in the form and arrangement of the connected parts, and is not limited to the precise embodiment thereof herein shown and described, as will readily be understood by those skilled in the art. It is evident, for 55 example, that the improvements are applicable to sewing machines employing a single needle in addition to multiple-needle sewing machines with which the improvements are primarily concerned.

Having thus set forth the nature of the invention, what I claim herein is:

1. In a multiple-needle sewing machine, the combination with a driving shaft and multiple non-rotary needle bars, of a reciprocatory driving connection between the

shaft and bars, retractible locking members carried by said connection one for each of the said bars, means for retracting the locking member for either of the said bars during the operation of the machine, and means 70 acting automatically to retain the released bar out of register with its locking member.

2. In a multiple-needle sewing machine, the combination with a frame, of a plurality of needle-bars mounted in said frame, a reciprocatory driving element adjacent said needle-bars, locking means carried by said driving element and automatically movable into engagement with each of said needle-bars, positively actuated means for retracting 80 said locking means and thereby disconnecting the driving element from either or all of said bars during the operation of the machine, and automatically acting means for throwing the released bar out of register 85 with its locking means.

3. In a multiple-needle sewing machine, the combination with a frame, of a plurality of needle-bars mounted in said frame, a reciprocatory driving element adjacent said 90 needle-bars, locking means carried by said driving element and automatically movable into engagement with each of said needle-bars, selective retracting members adapted to utilize the motion of the driving element 95 to retract the locking means from either of said needle-bars during the operation of the machine, and means independent of the retracting members for re-establishing the operative connection between each released 100 needle-bar and the driving element during the operation of the machine.

4. In a multiple-needle sewing machine, the combination with a frame, a plurality of needle-bars mounted to reciprocate within 105 said frame, a reciprocatory driving element embracing said needle-bars and movable with and also relatively to the same, bodily moving locking members carried by said driving element for securing each needle-bar to said driving element, and selective means for releasing the locking members with respect to either needle-bar during the 110 operation of the machine.

5. A sewing machine equipped with a 115 needle-bar or bars embraced by a yoke receiving reciprocatory movements from the main-shaft, said yoke being provided with a spring-pressed locking pin or pins corresponding in number to the number of 120 needle-bars, said locking pin or each locking pin having an enlargement at one end, the other end being adapted to enter an orifice in the needle-bar or the corresponding needle-bar, a wedge device or devices adapted or each adapted to be moved into operative engagement with the enlargement of said pin or corresponding pin to retract the pin from the orifice in the needle-bar, and spring means adapted on retraction of the 130

- pin or corresponding pin to raise the needle-bar or corresponding needle-bar to an extent greater than that of the normal upward movement imparted to it by the yoke.
- 5 6. In a multiple-needle sewing machine, in combination, a needle-bar actuating mechanism, a plurality of needle-bars capable of being separately operatively connected to and disconnected from said actuating mechanism, and a device stationary during the running of the machine and common to all said needle-bars, said device adapted on actuation to reestablish operative connection with the actuating mechanism of all the disconnected needle-bars simultaneously.
- 10 7. In a sewing machine, the combination with a reciprocating needle-bar and a yoke embracing the same adapted to impart movement thereto from the main-shaft, of a spring-pressed locking pin mounted within said yoke to engage a socket in the needle-bar, means for retracting said locking pin from the needle-bar during the operation of the machine, means for lifting the released needle-bar to an extent greater than that of the normal upward movement imparted to it by the yoke, and a vertically movable member arranged adjacent to the upper end of the needle-bar, said member being normally maintained by a spring in raised position out of engagement with said needle-bar, and being adapted on depression to force the released needle-bar downwardly so as to bring the socket of said bar 30 into register with the locking pin.
- 15 8. In a sewing machine having a plurality of bars carrying needles, a driving shaft, a reciprocating driving element between said shaft and said bars, said reciprocating driving element being detachably connected with a plurality of bars, means for effecting disengagement of the detachable bars from said reciprocating driving element, and independent means for moving the detachable bars to a non-engageable position relative to said reciprocating driving element.
- 20 9. In a sewing machine having a plurality of bars carrying needles, a driving shaft, a reciprocating driving element between said shaft and said bars, said reciprocating driving element being detachably connected with a plurality of bars, means for effecting disengagement of the detachable bars from said reciprocating driving element, and automatic means rendered effective upon the disengagement of the bars from said reciprocating driving element to move the detachable bars to a non-engageable position relative to said reciprocating driving element.
- 25 10. In a sewing machine having a plurality of bars carrying needles, a driving shaft, a reciprocating driving element between said shaft and said bars, said reciprocating driving element being detachably connected with said bars, each of said bars having manually operable means for disengaging the same from said reciprocating driving element, automatic means for moving each bar to an elevated position, and manual means for restoring the bars to engageable relationship with said reciprocating driving element.
- 30 11. In a sewing machine having a plurality of bars carrying needles, a driving shaft, a reciprocating driving element between said shaft and said bars, endwise movable pins for selectively coupling said reciprocating driving element to a plurality of bars, said pins being arranged for movement in parallel planes, and independent means for moving the detachable bars to a non-coupling position relative to said reciprocating driving element.

In testimony whereof, I have signed my name to this specification in the presence of two subscribing witnesses.
